SLIDER

Birdsall P. Lawson, New York, N. Y., assignor to
Ideal Fastener Corporation, Brooklyn, N. Y., a
corporation of New York

Application December 16, 1937, Serial No. 180,210

4 Claims. (Cl. 24—205)

This invention relates to improvements in sliders for slide fastener assemblies incorporating fastener elements or scoops mounted in offset relation with respect to the tapes.

5 Broadly, it is an object of this invention to provide, in a slide fastener assembly, wherein the fastener elements are mounted so as to normally rest in a plane angular with respect to the plane of the tape, for a slider of a construction and operation as to provide for interlocking and separation of the fastener elements on respective tapes in the transverse plane of the tape and that of the slider common thereto.

Specifically, it is an object of this invention to 15 provide for a novel construction of the lead end of a slider, whereby the slide fastener elements angularly mounted with respect to the transverse plane of the tapes carrying the same, acted upon by the slider, are displaced into the transverse 20 plane of the tape and the slider, both being common, as the fastener elements enter into the channels or guideways of the slider, thus providing for the disposition of the fastener elements in a requisite plane for interlocking or 25 separation by and within the slider.

These and other advantages, capabilities and features of the invention will appear from the subjoined detailed description of one specific embodiment thereof illustrated in the accompanying drawing, in which

Figure 1 is a perspective view looking upwards at a slide fastener assembly incorporating the slider forming the subject matter of this invention.

35 Figure 2 is a front elevation partially in section taken along lines 2—2 of Figure 1.

Figure 3 is a front elevation partially in section taken along lines 3—3 of Figure 1.

Figure 4 is a perspective view of the slider.

40 Figure 5 is a plan view looking upwards of the slider.

Referring to the reference characters in the drawing, numeral 10 represents a slider reciprocating upon cooperating stringers 11a and 11b, the flexible tapes 12a and 12b, of which carry scoops 14a and 14b, said scoops being clamped as shown in Figure 2 of the drawing to the flexible beads 13a and 13b at the ends of the tape.

As is indicated in Figure 2, the central trans- 50 verse plane of the tapes 12a and 12b is horizontal for the purpose of the embodiment herein illustrated, while the scoops 14a and 14b, as clamped to the beads of the tapes, have their transverse central plane normally at an angle with respect to that of the tapes; the transverse plane of the

slider is the same as that of the tapes, here being horizontal.

As shown in Figure 3, the scoops 14a and 14b when interlocked through the mating of their male and female cooperating elements 15 and 16, 5 are desired and required to be in a horizontal central transverse plane parallel to that of the tapes 12a and 12b.

As shown in Figure 1, which presents a "worm's-eye" perspective view of the stringers as 10 the same are acted upon by the slider 10 to interlock or separate the same, the upper portion of said view shows the normal positioning of the opposing stringers with the central transverse plane of the scoops at an angle to the central trans- 15 verse plane of the tapes carrying the same, while at the lower portion of such view the interlocked scoops have their central transverse plane parallel to that of the tapes and the slider.

As shown in Figures 1, 4 and 5, the slider 20 consists of a plurality of opposing wings 17 and 18, here shown as formed by stamping or die-casting, the upper wing 17 being narrower than the lower wing 18, the wings being united at one end by an integral connector post 19 adjacent which 25 there is disposed a separator member 20 of triangular formation, to provide a plurality of divergent channels 21a and 21b having a slightly larger and symmetrical cross-section than the scoops passing therethrough, and having a horizontal transverse plane, the diverging channels leading into a single or merging channel 22, so as to provide for the usual interlock and separator 30 action, whereby opposing stringer series 11a and 11b may be interlocked or separated, dependent 35 upon the directional reciprocation of the slider.

A handle portion 23 forming an integral extension of the connector post 19 extends above wing 17 and across the length thereof, and upon which handle there is mounted the tab 24 for 40 permitting the gripping and actuation of the sliders in the desired direction.

The lower wing 18 has upstanding walls 25a and 25b of height approximately that of the scoops 14a and 14b, while the upper wing 17 is 45 flat, to thus provide for enclosing side wall boundaries for the respective channels.

As shown in Figures 1, 3 and 5, the opposing faces of wings 17 and 18 are symmetrical and in parallel planes, except that the lower wing 18 is 50 shaped to provide a cut-out in the nature of arcuate segments, as 26a and 26b at the entrance of the diverging channels 21a and 21b defining the "leading" end of the slider; the arcuate edges 27a and 27b defining the cut-out being bevelled 55

or inwardly curved. The upstanding wall formations 25a and 25b of the wing 18 have a flared contour at their extremity, providing contacting edges or projections for tripping the scoops, as 5 will be later described.

As shown in Figure 1, as the slider 10 is displaced in the direction of the arrow, the leading edges or projections 28a and 28b of the walls 25a and 25b of the lower wing are adapted to contact with the upper portion of the clamping arm 10 as at 29a and 29b of the scoops 14a and 14b and as the slider is moved, to displace the scoops mounted in spaced relationship on the resilient tape, so that each of the scoops is displaced from its normal transverse central plane angular to the tape to a central transverse plane parallel to the tape; the cut-out segments 26a and 26b being of such extent that none of the remaining surfaces of the scoop, contact or impinge upon 20 any surface of said lower wing during such angular displacement of the scoops; thereafter, the scoops being in the transverse plane of the slider channels, further movement of the slider causes directive guidance of the scoops in the channels 25 for interlocking.

Since the scoops are firmly mounted in spaced relationship on the flexible bead of the flexible tape, the successive spaced scoops, adjacent the ones whose clamping surfaces are being acted on 30 by the contacting edges 28a and 28b of the walls 25a and 25b of the lower wing, are to a progressive decreasing degree displaced or twisted from the angular central transverse plane with respect to the tape to a plane less angular, with 35 the result that as successive scoops are contacted by the contacting edges 28a and 28b at the leading end of the wing 18, the scoops are more nearly in a position so that their central transverse plane is parallel to the normal tape plane; with 40 the result that the scoops as they enter into the divergent channels 21a and 21b between the wings, are in the proper horizontal central transverse plane desired for interlocking, which said interlocking takes place as the scoops of respective 45 stringers passing the separating post defining the divergent channels and enter into the single channel 22 where, they are presented with a central transverse plane parallel to the corresponding plane of the tape and of the channels of the slider.

It should be pointed out that conversely, when the slider is reversed in its motion to that direction shown by the arrow of Figure 1, the interlocked scoops as they are separated by the 55 separator post in passing from the merging to the diverging channels, and attain that zone of the lower wing 18 defining the cut-out segment, the tension on the tapes having been released, return to their normal angular position with relation to their central transverse planes and that of the tapes.

It is obvious that various changes and modifications may be made to the details of construction without departing from the general spirit 65 of the invention as set forth in the appended claims.

I claim:

1. In combination with flexible interlocking stringers, incorporating scoops normally mounted in a central transverse plane angular to that of the tapes carrying the same, a slider compris-

ing a body portion formed of opposing wings, one above the other, spaced to provide diverging channels merging into a single channel, said channels having their axes parallel to and below the transverse plane of the tapes, and means 5 on one of said wings at the leading end of the diverging channels for displacing the scoops from the normal angular position aforesaid to that wherein their central transverse planes are in parallelism to that of the tapes upon actuation 10 of said slider.

2. In combination with flexible interlocking stringers incorporating scoops normally mounted in a central transverse plane angular to that of the flexible tapes carrying the same, a slider comprising upper and lower spaced wings and a post connecting the same to provide diverging channels merging into a single channel, the channels having their axes parallel to and below the transverse plane of the tapes, and formations on 15 the lower of said wings at the leading end of the diverging channels defined thereby, and acting on the scoops upon entry of the same therein, for displacing such scoops from their normal position aforesaid to one wherein their central transverse plane is parallel to that of the tapes, upon 20 actuation of said slider.

3. In combination with flexible interlocking stringers, incorporating scoops normally mounted in a central transverse plane angular to that of the tapes carrying the same, a slider comprising a plurality of spaced wings, and a post connecting the same to define diverging channels merging into a single channel, said channels having their axes parallel to and below the transverse 30 plane of the tapes, one of the wings at its end defining the diverging channels having a cut out formation and a projection thereadjacent, the other wing extending opposite the projection and a cut out formation, the projection on said 35 first named wing serving on displacement of the slider to contact with and act upon a scoop entering into the leading end of the diverging channels as the same rests above the cut out formation of said wing to displace said scoop from its angular plane of mounting on the tape aforesaid to that wherein its central transverse plane is in 40 parallelism to that of the tape.

4. In combination with flexible interlocking stringers, incorporating scoops normally mounted in a central transverse plane angular to that of the tapes carrying the same, a slider comprising upper and lower wings and a post connecting the same to define diverging channels merging into a single channel, said channels having their 50 axes parallel to and below the transverse plane of the tapes, the lower of said wings at its end defining the diverging channels having a cut out formation and a projection thereadjacent, the other wing extending opposite the projection and a cut out formation, the projection on said first 55 named wing serving on displacement of the slider to contact with and act upon a scoop entering into the leading end of the diverging channels as the same rests above the cut out formation of said wing to displace said scoop from its angular plane of mounting on the tape aforesaid to that wherein its central transverse plane is in parallelism to that of the tape.
